UNITED STATES PATENT OFFICE.

WILLIAM STEPHENS, OF SOMERVILLE, MASSACHUSETTS, ASSIGNOR TO SAMUEL STEPHENS AND WICKERSHAM QUOIN COMPANY, OF BOSTON, MASSACHUSETTS, A CORPORATION OF MASSACHUSETTS.

TYPE CABINET OR THE LIKE.

Application filed August 10, 1927. Serial No. 212,012.

My present invention relates to equipment for composing rooms and more particularly aims to provide an improved type cabinet, case rack or stand, or the like for use by com-
5 positors, students of composing and others.

In the drawings illustrating by way of example certain embodiments of my invention:

Fig. 1 is a front elevation of a type cabinet or the like in accordance with one form of my
10 invention, the lower portion of the cabinet being broken away;

Fig. 2 is a side elevation of the cabinet of Fig. 1 as viewed from either side;

Fig. 3 is a plan view of the cabinets of Figs.
15 1 and 2; and

Fig. 4 is a view corresponding to Fig. 1 illustrating a modified construction also embodying my invention.

Referring more particularly to the drawings and first to Figs. 1 and 2, the invention is shown, for the purpose of illustration, in connection with a type cabinet, the body 1 of which may be of any suitable standard or other form, with provision for the support of
20 one, two or more tiers of type cases or draws, accessible at the front 2 of the cabinet intermediate the cabinet sides 3, 3. Supports for a single tier of such cases are indicated at 4 in Fig. 1. Said type cases may be included in a
25 single body as illustrated or, if desired, two or more structurally separate tiers may be placed together for use as a unit under a single cabinet top. If more than a single tier of cases is employed side-by-side, however, they
30 should not substantially exceed a standard single tier width, that is, a total width such as to enable compositors standing at the opposite sides of the cabinet conveniently to reach the centrally disposed lead-and-slug racks ex-
35 tending from front to rear of the cabinet, as hereinafter described; or, if desired, two normal width tiers may be disposed oppositely and back-to-back under the cabinet top or tops, together affording working space for
40 four compositors, two at each side of the front-to-back opening type-case tiers. My invention is also useful in connection with
45 composing room equipment commonly known as case racks or case stands, as well as with
50 type cabinets proper.

Further, my present invention is particularly useful with type cabinets or the like generally known as school cabinets or window cabinets, intended for use by two compositors,

and especially by student compositors work-
55 ing facing each other, one at each side of the cabinet. Cabinets of this type are also adapt-
ed to be placed with their back near or against a window, affording equal light to the two
60 persons standing at right-angles to the window and at opposite sides of the cabinet. It will be understood that the front of the cabinet, as herein referred to, is that face 2 ap-
65 pearing in Fig. 1, at which the type draws or cases are inserted or removed, and that the cabinet sides 3, 3, one of which is seen in Fig. 2, are those opposed faces at right-angles to said front 2 of Fig. 1.

At the top of the cabinet, at the two oppo-
70 site sides thereof, is provided any desired means for holding the work and materials
75 with which the respective compositors are occupied. Such means may be in the form of inclined brackets 5, 5, etc., as seen in Figs. 1 and 2 or may be otherwise constructed, as in the form of a continuous work-bank along the
75 respective side top portions of the cabinet.

Heretofore it has been necessary for com-
80 positors or students working at the sides of a cabinet of this school or window form to leave their working position to obtain spacing ma-
85 terials such as leads and slugs, going either to the front of the cabinet or to some other and still more distant point. In accordance with my present invention I have provided means
85 whereby the person working at either side of such cabinet may at all times have immediate-
90 ly before him an adequate supply of spacing materials, including leads or slugs or both.

Referring to Figs. 1, 2 and 3 said means
95 preferably comprises one or more racks or rows of compartments, desirably vertically opening, extending in a direction from front to rear of the cabinet and substantially at right-angles to the cabinet front 2, with their vertical openings accordingly facing the compo-
100 sitor for whose use they are intended. In said Figs. 1 to 3 I have shown a tier comprising two racks, each rack having a series of compartments, one rack for leads and the other for slugs. As illustrated, the upper rack 6 with compartments 7 is arranged to accommodate slugs in lengths from 10 to 40 by ems, while the lower rack 8 having com-
105 partments 9 will accommodate a correspond-
ing supply of leads similarly arranged. The compartments of the two racks are desirably numbered with the appropriate size of lead or

slug, as indicated at 10, 10. Depending upon the different circumstances and conditions under which the cabinets will be used, a greater or less number of racks may be employed, 5 with a corresponding variation in the supply of materials accommodated and if desired a single rack arranged to hold leads at one portion and slugs at another portion may be provided.

- 10 Said spacing materials rack or racks of vertical opening compartments are disposed to face the person working at the respective cabinet side, being supported in said position in any suitable manner so as to be readily accessible. In said Figs. 1, 2 and 3 they are shown by way of example as positioned above and near the rear of the work space at the respective top side portions of the cabinet, where they are supported as by the posts 11, 15 20 11 near the front and rear of the cabinet, respectively, and substantially centrally thereof from side to side.

The row or rows of compartments, or racks 6, 6, 8, 8, for the two opposite sides of the cabinet, in the construction of Figs. 1 to 3, are positioned back to back and oppositely, so that the shallower compartments of one rack, for receiving the shorter leads or slugs, will lie opposite the deeper compartments, for 25 receiving the longer leads and slugs, of the other rack, as clearly seen in Fig. 3. The rear walls 12 of the several compartments thus lie along an inclined line in the manner readily apparent in said figure.

30 35 From the foregoing it will be understood that in accordance with my invention, each compositor, one working at each side of the cabinet, will have before him one or more lead racks or one or more slug racks, or both as in the construction illustrated, each such rack comprising a series of compartments, 40 preferably with vertical openings facing the respective sides although any other desired form of compartment, such as top opening, 45 may be employed. The vertically opening construction, however, such as illustrated, is deemed preferable particularly in the case of leads and slugs.

In Fig. 4 I have shown a somewhat modified construction wherein racks 13, 13 comprising compartments 14 and racks 15, 15, comprising compartments 16, are set into the cabinet along the opposite sides thereof and below the respective working spaces. The 50 55 compartments may be substantially similar to those described in connection with Figs. 1 to 3. Said construction of Fig. 4 may be preferable in certain cases, for example, where it is desired to utilize substantially the entire 60 cabinet top for working purposes or for any other reason.

Whatever be the precise location utilized, whether that of Figs. 1 to 3, Fig. 4 or other, I believe myself to be the first to provide a 65 type cabinet, case rack or stand having a

rack or row of vertically opening or other compartments for leads and/or slugs extending substantially at right-angles to the cabinet front and in the direction from front to rear, thereby immediately accessible to a person working at a side of the cabinet. 70

My invention is not limited to the particular embodiments thereof herein shown and described, its scope being set forth in the following claims. 75

I claim:

1. A type cabinet particularly adapted for school purposes and/or for use at or near a window, comprising, in combination, type drawers mounted for insertion and withdrawal at the cabinet front, means along the opposite cabinet sides for holding the work of a compositor facing the cabinet at that side, and a plurality of opposed vertical lead and/or slug racks arranged back to back, one opening toward each cabinet side and extending therealong substantially from front to rear, whereby compositors working one at each side of the cabinet may have before him a supply of leads and/or slugs, and may each work at his cabinet side without interference to the continued working of one during removal or replacement of type drawers by the other. 80 85 90 95

2. In a type cabinet, case stand or the like, one or more tiers of type drawers opening at the cabinet front and having a total width not substantially exceeding that of a standard single type-drawer tier, a working space along each side of the cabinet, and racks comprising each a series of compartments for holding leads and/or slugs, one or more of said racks for each side of the cabinet, oppositely disposed, extending in the direction from front to rear of the cabinet, and accessible respectively to persons working one at each cabinet side, whereby a cabinet of not greater than standard single-tier width may be utilized simultaneously by two persons without interference to the continued working of one during type-drawer removal or replacement by the other. 100 105 110

3. In a type cabinet, case stand or the like, one or more tiers of type drawers opening at the cabinet front and having a total width not substantially exceeding that of a standard single type-drawer tier, a working space along each side of the cabinet, and, for each side of the cabinet, two superposed racks each comprising a series of vertically opening compartments, one rack for leads and the other for slugs, said racks extending substantially at right angles to the cabinet front, the racks for the two sides being oppositely disposed with their openings facing the respective cabinet sides, whereby said cabinet as a whole, while not exceeding standard single-tier width, accommodates two working persons, one at each side thereof without interference to the continued working of one 115 120 125 130

during type-drawer removal or replacement by the other.

4. In a type cabinet, case stand or the like, one or more tiers of type drawers opening at the cabinet front and having a total width not substantially exceeding that of a standard single type-drawer tier, a working space along each side of the cabinet, and, for each side of the cabinet, a rack comprising a series of vertically opening compartments for leads or slugs, said racks extending substantially at right angles to the cabinet front, being oppositely disposed and juxtaposed back to back, and means on the cabinet to support said racks near the inner portions of 15 and above the respective working spaces and substantially centrally of the cabinet from side to side, the latter having a width not greater than such as to bring said centrally disposed racks within ready reach of the 20 workers at the respective cabinet sides.

In testimony whereof, I have signed my name to this specification.

WILLIAM STEPHENS.
